Primary Examiner — Cynthia M Chin*(74) Attorney, Agent, or Firm* — Kevin Pumm(57) **CLAIM**

The ornamental design for a toy play set fence, as shown and described.

DESCRIPTION

FIG. 1 is a perspective view of a toy play set fence, showing my new design;

FIG. 2 is a front elevation view thereof;

FIG. 3 is a left side elevation view thereof;

FIG. 4 is a right side elevation view thereof;

FIG. 5 is a back elevation view thereof;

FIG. 6 is a top plan view thereof; and,

FIG. 7 is a bottom plan view thereof.

The broken line details shown in FIG. 3 represent environmental subject matter and forms no part of the claimed design.
